UNITED STATES PATENT OFFICE

164,490

YOUTH CHAIR

Bertis F. Hamilton, Columbus, Ind.

Application July 24, 1950, Serial No. 11,371

Term of patent 14 years

(Cl. D15—1)

To all whom it may concern:

Be it known that I, Bertis F. Hamilton, a citizen of the United States, residing at Columbus, Bartholomew County, Indiana, have invented a new, original, and ornamental Design for a Youth Chair, of which the following is a specification, reference being had to the accompanying drawings, forming part thereof.

Fig. 1 is a side elevation, Fig. 2 is a front elevation, and Fig. 3 a top plan view of a youth chair embodying my new design.

I claim:

The ornamental design for a youth chair, as shown.

BERTIS F. HAMILTON.
